(57) **CLAIM**

The ornamental design for a two burner stove with folding shelf lid, as shown.

DESCRIPTION

FIG. 1 is a perspective view of a two burner stove with folding shelf lid with the lid in an open position;

FIG. 2 is a perspective view with the lid in a closed or folded position;

FIG. 3 is a front elevational view;

FIG. 4 is a left side view, the right side view being a mirror image thereof;

FIG. 5 is a top plan view;

FIG. 6 is a rear elevational view; and,

FIG. 7 is a bottom plan view.

The details shown in broken lines in FIGS. 1 and 5 are for illustrative purposes only and form no part of the claimed design.
